UNITED STATES PATENT OFFICE

GUSTAVE E. VILLARET, OF LEONIA, NEW JERSEY, ASSIGNOR TO MARKEL ELECTRIC PRODUCTS, INC., OF BUFFALO, NEW YORK, A CORPORATION OF NEW YORK

DESIGN FOR AN ELECTRIC-LIGHT FIXTURE

Application filed November 5, 1929. Serial No. 33,343. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for an Electric-Light Fixture, of which the following is a specification, reference being had to the accompanying drawing, forming part thereof.

In said drawing:

Figure 1 is a top plan view of an electric light fixture embodying my new design comprising five lamp supporting arms all equidistantly spaced, two arms and the portion

of the fixture therebetween being shown in full lines and the remainder of the fixture involving repetition of the portion shown in full lines being indicated diagrammatically in outline.

Figure 2 is a vertical elevation of the same, half of the fixture being shown completely by full lines and the other half involving repetition of the pattern being indicated diagrammatically in marginal outline.

I claim:

The ornamental design for an electric light fixture, substantially as shown and described.

GUSTAVE E. VILLARET.
